CARD HOLDER

Franklin H. Thompson, Indianapolis, Ind.

Application May 22, 1933. Serial No. 672,086

1 Claim. (Cl. 40—11)

This invention relates to the art of means for hanging or supporting cards, tags, tickets and the like, such, for example, as is found in the practice of stores wherein price tags are hung from shelving to designate prices of articles thereon. A primary object of the invention is to provide a structure which may be applied to and removed from a tack without having to withdraw the tack and at the same time retain the holder about the tack against accidental displacement. A further important object of the invention is to provide a very simple structure capable of being produced at a low price so that it may be employed freely without undue restriction as to cost. A still further important object of the invention is to provide a holder of the nature indicated which will be neat in appearance, will have a considerable portion of the supporting member concealed by the head of a tack so that it will be unobtrusive and not detract from the appearance of the card or tack support. A still further important advantage of the invention is to provide a tag holder of such formation that the end to be carried by a tack will also serve as a convenient handle by means of which the holder is engaged with the card or tag.

These and other objects and advantages will become apparent to those versed in the art in the following description of the invention which is made in reference to the accompanying drawing, in which

Fig. 1 is a fragmentary front elevation of a device embodying my invention supporting a price tag;

Fig. 2, a top plan view;

Fig. 3, a front elevation showing the device about to be positioned on the supporting tack;

Fig. 4, a side elevation of the holder, and

Fig. 5, a top plan view in diagrammatic form indicating the various positions of the holder as it may be placed on the supporting tack.

Like characters of reference indicate like parts throughout the several views in the drawing.

The device embodying my invention is preferably formed by bending a piece of wire to have a plurality of overlapping turns 10, here shown as two in number, the turns being circular. In the preferred form, the end of the back turn terminates as at A, Fig. 4, at the top of the turns, and furthermore, extends slightly above the outside of the adjacent turn.

From the upper end of the front turn, the wire is carried vertically upward to form a short shank 11 and is then curved around upwardly and thence back downwardly toward the shank to form an

upper loop 12 generally elliptical in shape, the essential feature being that the major vertical inner length of the loop be equivalent to or slightly in excess of the diameter of the head 13 of a supporting tack and that the transverse width be less than the diameter of this head, this transverse width being equal to the radius of the head plus the radius of the shank of the tack plus a clearance length sufficient to permit the loop being entered by one side under the tack 65 head 13 as indicated in Fig. 3 to have the entered side carried on over against the tack shank 14 as indicated in Fig. 5 to permit the other side of the loop to be then swung around to the dotted line 70 position back of the head to have the loop plane 75 parallel with the back of the tack head so that the loop may then be released to have it drop down to hang on the shank 14 as shown in Fig. 1. In any event the width of the loop between the opposing sides is less than the diameter of the 75 head 13 so that it is necessary to shift the loop laterally to have one side of it contact the shank of the tack and then rotate the loop to have the other side of the loop carried around in front of the head before the holder may be disengaged 80 from the tack. It is desirable that the tack be left in the wood shelving 15 without having to be removed and replaced at each change in price necessitating a change in the price tag so that the edge of the shelving is not being marred by 85 tack holes any more than is absolutely necessary.

The price tag 16 here shown as being carried by the holder is engaged with the holder by placing the loop 12 downwardly over the face of the tag 90 to have the upper edge of the tag enter under the end A between it and the adjacent loop 10, the tag being pushed thereunder until it strikes the opposite side of the loop, following which the loop 12 is engaged and rotated to swing it upwardly to the position indicated in Figs. 1 and 3. The loop 12 being of an elongated nature is easily held under this operation. When a customer removes an article from a shelf as he would in a "self serving" store, and in so taking the article 100 happens to strike the price tag, the holder will be retained on its supporting tack even though it be knocked upwardly since there must be a rotation of the holder simultaneously with the upward lifting before the loop 12 can be disengaged from the tack. It is to be noted that the tack is not driven into the wood shelving completely but is only inserted therein sufficiently to retain it and still permit sufficient clearance between the shelving and the head for the inser- 110

tion of the loop 12 thereunder. This clearance need not be greater than a distance slightly in excess of the diameter of the wire of the loop. With the weight of the price tag on the holder, 5 the loop 12 is ordinarily maintained in the position indicated in Fig. 1 so that there is no tendency of the price tag to swing horizontally about the vertical axis of the holder.

While I have herein shown and described my 10 invention in the one best form as now known to me, it is obvious that structural variations may be employed without departing from the spirit of the invention and I therefore do not desire to be limited to this precise form beyond the limitations as may be imposed by the following claim.

I claim:

In combination with a tack having a head and a shank, a card holder formed from wire comprising a plurality of circular turns one elastically pressing against the other and a non-circular loop 80 extending from the turns having a vertical length sufficient to permit the loop being entered over said tack head and having a width less than the tack head width whereby the loop to be passed over the tack head is required to be entered by 85 one side under the head and brought thereunder against said tack shank to permit the other loop side to be swung around the tack head edge.
